UNITED STATES PATENT OFFICE

ELMER E. BISHOP AND FRED J. BROOK, OF INDIANAPOLIS, INDIANA

STATIC ELIMINATOR

Application filed February 25, 1929. Serial No. 342,436.

This invention relates to certain improvements in devices for eliminating the static influences and interference in radio communication. The device herein disclosed is especially intended for use in connection with radio receiving sets and circuits for eliminating the static interference from the incoming signals.

The static eliminator herein disclosed is similar in some respects to that disclosed in an application of Lulu H. Bishop for Letters Patent of the United States on radio reception, Serial No. 265,591, filed March 29, 1928, as administratrix of the estate of James A. Bishop. In that application there is disclosed an arrangement in which the incoming signals are carried through a conductor or conductors in proximity to a magnetic field or fields so that the static interference is drawn away from said conductors by a magnetic action. The static interference is thus separated from the true radio signals, allowing the latter in substantially undiminished and in greatly clarified form and tone to enter the translating apparatus of the system.

In the arrangement disclosed in that earlier application, the conductor or conductors are carried through tubular magnetic shields which are in turn subject to the control and influence of magnets whereby they are magnetized, and in the arrangement of that application these magnets are illustrated as being of electro-magnetic influence. Furthermore, in the arrangement of that earlier application of the magnetic shields and all portions of each shield are subjected to the same magnetic polarity.

According to one feature of the present improvements we have provided an arrangement in which the tubular magnetic shields are subjected to both positive and negative magnetic influences so that each of said tubular magnetic fields constitutes a portion of a magnetic circuit through which the magnetic lines of force flow from one pole of the magnet to the other. That is to say, each of the magnetic shields is simultaneously subjected to the influences of both positive and negative magnetic polarity, whereas in the aforesaid earlier application each of said

shields is subjected at all points to one and the same polarity.

Furthermore in the present arrangement we have found it possible to make use of permanent magnets for generating the magnetic fields, and we are enabled to do this largely because of the fact that each of the magnetic shields is subjected to both the positive and negative magnetic influences.

Permanent horseshoe magnets of relatively small size can thus be used with very satisfactory results, and magnets of this kind can be produced which will be sufficiently powerful and permanent to give very fine and lasting operation.

A further feature of the invention relates to accomplishing a very complete and thorough elimination of the objectionable static influences.

Other objects and uses of the invention will appear from the detailed description which consists of the features of construction and combination of parts hereinafter described in the claims.

In the drawings:

Figure 1 shows a plan view of a device embodying the features of the present invention;

Figure 2 shows a fragmentary side elevation corresponding to Figure 1 but on enlarged scale;

And Figure 3 shows a cross section on the line 3-3 of Figure 1, looking in the direction of the arrows, but on enlarged scale.

We have shown the features of our invention as incorporated within a structure including two units, 4 and 5 mounted upon a common baseboard 6. Said baseboard is preferably made of wood, fiber, composition material, or other suitable material, preferably of a non-magnetic nature.

Each of the units 4 and 5 includes a horseshoe permanent magnet 7, the poles 8 and 9 of which are brought into parallelism in the usual manner. Also said poles are preferably of alternate polarity as indicated by the markings shown upon them.

Secured to the top and bottom faces of each of the magnetic poles there is a plurality of relatively thin sheets or laminations

10 of magnetic material such as a high grade of soft iron. The number of these laminations in each group will depend upon the number of tubular magnetic shields of such 5 group. The number of laminations on each magnet pole should be equal to the number on the other end.

Each of the tubular magnetic shields comprises a coil or helix 14 of magnetic wire 10 such as soft iron wire. The same is wound into a close coil of proper diameter and of proper length to overlie the laminations reaching out from the North and South poles of the magnet in question. This general arrangement will be well understood from examination of Figure 1.

The end portions 15, of the laminations are coiled around the respective tubular magnetic shields so as to accomplish the two purposes of holding said shield securely in place 20 and at the same time establishing a thorough magnetic contact therewith.

The successive laminations of each bunch are of progressively shorter lengths as best 25 shown in Fig. 2 so that the tubular magnetic shields will be located side by side to each other when secured in place. This is well illustrated in Figure 2.

From the foregoing it will be evident that 30 the number of laminations from each pole is equal to the number of tubular magnetic shields of that unit.

It will also be evident that the magnetic flux passes from each North pole to the other 35 corresponding South pole, passing as it does so through all of the tubular magnetic shields of that unit.

An aerial or antenna wire or wires 16 are threaded through the shields in the proper 40 manner to effect the elimination and remove all static influences. The principles of this operation are similar in some respects to those disclosed in the aforesaid earlier application for Letters Patent of the United 45 States. In this connection the aerial conductor is preferably threaded back and forth through the top and bottom tubular shields of each unit in succession so that when the conductor is completely interwoven with the 50 shield it will present an appearance such as shown in Figure 2 when viewed from one side.

It will be found that the static interference 55 or influence is drawn into the magnet poles and may be thence discharged into the ground or atmosphere. For this purpose the poles of the two units are shown as being electrically connected together by a conductor 17, and there is also shown another conductor 18 which may be grounded.

We have found by experimentation that 60 this type of construction may be made amply strong for all practical requirements as far as the magnetic connections are concerned, 65 and that the construction herein disclosed

may be incorporated into a very compact and relatively small structure.

While we have herein shown and disclosed only a single embodiment of the features of our invention, still we do not intend to limit ourselves in the same except as we may do so in the claims.

We claim:

1. In a device of the class described the combination of a horseshoe shaped permanent magnet, equal numbers of laminations of magnetic material projecting from and secured to the polar surfaces of said magnet, tubular shields of magnetic material extending between corresponding laminations projecting from opposite magnetic poles, a conductor for radio frequency currents threaded through the tubular magnetic shields in sequence, and a ground connection to the magnet, substantially as described.

2. In a device of the class described the combination of a horseshoe shaped permanent magnet, a series of laminations of magnetic material secured to and projecting from each magnetic pole, the number of laminations in one series being the same as that in the other series, tubular shields of magnetic material extending between corresponding laminations reaching from the two poles of the magnet, and a conductor for radio frequency currents threaded through said magnetic shields in sequence, substantially as described.

3. In a device of the class described, the combination of a horseshoe shaped magnet, a plurality of laminations secured to and extending outwardly from each pole of said magnet, tubular shields of magnetic material extending between the laminations of the two poles, and a conductor for radio frequency currents extending through said shields in sequence, substantially as described.

4. In a device of the class described the combination of a pair of magnetic poles of opposite magnetic polarity, a series of laminations of magnetic material secured to and reaching outwardly from each of said magnetic poles, a series of tubular shields of magnetic material extending between laminations of the two poles, and a conductor for radio frequency currents extending through the tubular shields in succession, substantially as described.

5. In a device of the class described the combination of a pair of magnet poles of opposite polarity, a series of tubular shields of magnetic material having their end portions magnetically connected to the opposite magnetic poles, and a conductor for radio frequency currents threaded through said tubular shields in succession, substantially as described.

6. In a device of the class described the combination of a pair of magnetic poles of

opposite polarity, a tubular shield of magnetic material having its opposite ends in magnetic connection with said opposite magnetic poles, and a conductor for radio frequency currents extending through said shield, substantially as described.

5 7. In a device of the class described, the combination of a pair of magnetic poles of opposite polarity, a tubular shield of magnetic material joining said poles together and constituting a portion of the magnetic circuit, and a conductor for radio frequency currents extending through said shield, substantially as described.

10 8. In a device of the class described the combination of a pair of magnetic poles of opposite polarity, two groups of tubular shields of magnetic material lying in parallelism and having the end portions of each 15 said shield magnetically connected to the opposite magnetic poles, and a conductor for radio frequency currents extending through said tubular magnetic fields, substantially as described.
